MACHINE FOR MILLING LUMBER AND THE LIKE

Filed Aug. 18, 1924

INVENTOR.

Ray W. Scott

UNITED STATES PATENT OFFICE.

RAY W. SCOTT, OF LOS ANGELES, CALIFORNIA, ASSIGNOR OF ONE-HALF TO RADIO LAB. & MFG. CO., A COMMON-LAW TRUST ASSOCIATION OF CALIFORNIA, AND ONE-HALF TO LEON H. SCOTT, OF PASADENA, CALIFORNIA.

MACHINE FOR MILLING LUMBER AND THE LIKE.

Application filed August 18, 1924. Serial No. 732,629.

The object of my invention is to provide a suitable machine for the manufacture of a perforated board preferably of wood by cutting a plurality of holes therein at a high rate of speed facilitating intense manufacture and producing a perforated lath or sheeting board for plastered walls in substitution for the ordinary lath.

A further purpose of the machine is to manufacture such perforated boards with perforations having tapered walls forming larger openings on one side and smaller openings on the other. When the boards are nailed upon a wall to be plastered, such perforations, or apertures, thus being adaptable to form keys for the securing of the plaster to the walls or other uses to which such perforated boards may apply.

The introduction of metal lath and plaster boards have made great inroads into the lumber business so far as the ordinary lath is concerned, and such a product as my machine would reestablish upon a competitive basis a wooden material for this purpose. My invention thus overcomes the objection to old-fashioned lath and has many advantages over all substitutes inasmuch as it adds great strength to the building, can be nailed in place by anyone without the aid of a skilled lather, requires less mortar to construct a plastered wall and has many other advantages. Other objects and advantages of my invention are particularly cited in the following description and indicated in the appendant claims.

In pursuance of the mentioned objects, I have utilized in my machine, a principle involving the perforating of boards by means of circular saws or grubs, these being preferably carried by and disposed partly within a cylinder, turning with the same while simultaneously rotating about their own spindles, planetary fashion,—such rotation being adapted to a function effectively to cut the said perforations as each board is fed through and between pairs of the cylinders,—the rotating saws being in all cases successively carried to and from operative positions by automatic or cyclical movements in planes substantially perpendicular to the sawed surfaces of said boards and parallel with the direction of advance of said boards.

My invention is illustrated by the accompanying drawings, which, with their reference numerals, form a part of this specification. Like reference numerals indicate like parts in all of the drawings.

Figure 1 is a side elevation diagrammatically showing a wood-working or milling machine embodying my invention.

Figure 2 is a partial top plan view, on an enlarged scale.

Figure 3 is a vertical sectional detail view, corresponding to the central portion 65 of Fig. 1, and showing the manner in which perforating saws may be so mounted in the cylinders as to protrude through the periphery thereof.

Figure 4 is a detail showing gears by 70 which the shafts carrying the mentioned cylinders may be synchronously rotated.

Figure 5 is a schematic illustration of an alternative form hereinafter referred to.

In Figure 1, I show a substantial frame 75 1, carrying feed rollers 2, which are adapted to hold a board 3 down upon the top of said frame, at the same time forcing the board 3 forward and advancing it along a table above and below which I may dispose milling or perforating cylinders 4. These cylinders may have the same peripheral speed as the mentioned board, forcing the same onward and into engagement with independently driven saws hereinafter mentioned, suitable driving means being provided, as later described, for maintaining the proper rotation of the mentioned cylinders and rollers during the rotation of the saw spindles 5 within said cylinders,—the 90 mentioned construction being such as to apply power to the saws, for the cutting of slots in the board, during its advance.

In Figure 2, I have shown a portion of the frame 1, the board 2, and the upper 95 cylinder 4, the latter being carried on a shaft which rotates in bearings 7; and I also show driving pulleys 8 of the saw spindles 5 and one of a pair of intermeshing gears 9, the uppermost of these gears 100 engaging a like gear on the shaft of the lower cylinder, to maintain synchronous rotation between the two,—the board 3 being shown with perforations cut in that portion which is passed between the mentioned cylinders, and the upper and lower

cylinders being provided with complementary saws which are adapted to operate on opposite sides of a board, during its passage between said cylinders, or their equivalents.

5 In a machine provided with a surfacing head, as shown at 10. Figure 1, any desired number of pressure feed rollers 2 may be so used as to press the board 3 down against the top of the frame 1 and into contact with 10 said surfacing head; and the machine may be provided with other standard cutting heads, for forming any special contour of the board.

Power from a suitable source may be applied to the shaft 11, upon which is shown mounted a pulley 12 of sufficient width to carry the various belts for driving a pulley 13 and also the feed rollers 2; and any surfacing head 10 may be driven in the direction suggested by the arrow on the pulley 12. Carried in suitable bearings on the frame 1 are shown shafts 14, supporting the mentioned perforating cylinders 4. The cylinders 4 are geared together by the timing gears 9 (Figure 2 and Fig. 4), so as to establish a perfect alternation of perforations within the board from above and below, somewhat as best shown in Figure 3. The upper cylinder 4 may be driven from the shaft of the feed roller 2 by means of the chain belt 15 and suitable sprockets, and the lower cylinder 4 may be driven from the upper cylinder through the timing gear 9. Independently to drive saws 6, or their equivalents, suitable spindles 5 to which the small saws 6 are secured are rotatably mounted within the cylinders 4 in such a way that the saws protrude through the periphery of the cylinder in the proper degree to make the desired cut in the board 3 (Figure 3). Secured to the protruding end of each of the saw spindles 5, are the driving pulleys 8, which may be belted to the pulley 13, one belt in each case passing around the entire circle of pulleys and applying power to the spindles 5 only when the belt contacts with the pulleys. This however, is sufficient inasmuch as the saw spindles 5 require no power when the saws do not engage the board. The feed rollers 2 are driven in the direction shown by the arrow and are adapted to force the board beneath them and between the cylinders 4 while the cylinders 4 move in the same direction with relation to 55 the board, and at the same time the saws bodily advancing therewith, are driven independently at a high cutting speed and in opposite rotation to cylinders 4. The lower system of pulleys 8 may be driven from the pulley 13 through the belt 16, the counter-pulley 20, and the belt 21.

At the extreme left of Figure 1 I may provide a band saw wheel 17 adapted, in conjunction with a similar wheel, to carry a band saw shown as driven by the belt 18,

the band saw traversing horizontally in such a manner as to sever the board longitudinally into resultant boards of undiminished breadth as it passes through the cylinders 4. Fig. 5, being merely diagrammatic of 70 alternative means for perforating, no band saw is shown therein.

It will now be seen that if a board of approximately the proper thickness is passed through the machine from the right beneath 75 the feed rollers 2, it will be forced against the surfacing cutter head 10 and forward between the perforating cylinders 4 which in turn grip the board between their peripheral surfaces and thereby serve also to 80 draw the board forward and force the same against the band saw 19 (Figures 1 and 3). The rotating cutter saws carried by the moving cylinders are brought in contact with the board in the regular path of rotation of 85 the cylinders and as the rotation of the saws shown by the arrow (Figure 3) is against the direction of the board, each will cut itself into and slightly more than half way through the board and move out of the cut 90 as soon as the cylinder passes around in its rotation, the resultant apertures being outwardly divergent, although produced during the uninterrupted advance of the boards at the peripheral speed of the cylinders 4. 95 Now the depth of the saw cut in the board 3 is established by the protrusion of the saws from the cylinders 4, so that, when the band saw subdivides the board as shown, the finished product will comprise pairs of like 100 boards perforated through and through with apertures having larger openings on one side of the board than on the other.

What I claim is:

1. In a machine for milling lumber or 105 the like, the combination of means adapted to force a board through said machine and independently driven rotating means advancing therewith for perforating the board continuously during its uninterrupted advance, 110 said saw means being effective automatically to advance and to retract saws in planes parallel with said advance and in such manner as to cut separate outwardly expanding slots in said boards.

2. In a machine for milling lumber or the like, the combination of means adapted to force a board through said machine and independently driven rotating means advancing therewith for perforating the board continuously during its uninterrupted advance and means for bisecting the board, said saw means being effective automatically to advance and to retract saws in planes substantially perpendicular to the sawed surfaces of 125 said board.

3. In a machine for milling lumber or the like, the combination of means adapted to force a board through said machine; means for perforating the board during its uninter- 130

rupted advance and means for bisecting the board, said perforating means comprising circular saws rotated within rollers and protruding therefrom and adapted to cut their way into the surface of the board; and means for timing the rotations of said saw-carrying rollers.

4. In a machine of the character described: means for advancing a board; and 10 rotary saw means comprising saws which rotate in planes parallel with the direction of said advance and which are caused cyclically to approach and withdraw in said planes for a simultaneously cutting outwardly divergent openings extending more than half way therethrough from opposite sides

of said board, during its uninterrupted advance.

5. In a machine of the character described: means for advancing a board; and 20 means comprising rotary saws successively moved to and from operative positions, for cutting outwardly divergent and interrupted openings which extend more than half way therethrough from opposite sides of said 25 board, during its uninterrupted advance; and means for so subdividing said board that said openings extend completely through the resultant boards.

In testimony thereof, I affix my signature.

RAY W. SCOTT.
